UNITED STATES PATENT OFFICE.

CHARLES R. SCHLEIFER, OF CEDARBURG, WISCONSIN, ASSIGNOR TO EXCELSIOR SHOE & SLIPPER COMPANY, OF CEDARBURG, WISCONSIN.

SHOE.

No. 877,869.

Specification of Letters Patent.

Patented Jan. 28, 1908.

Application filed May 14, 1906. Serial No. 316,620.

To all whom it may concern:

Be it known that I, CHARLES R. SCHLEIFER, a citizen of the United States, residing at Cedarburg, county of Ozaukee, and State of Wisconsin, have invented new and useful Improvements in Shoes, of which the following is a specification.

My invention relates to improvements in that class of shoe uppers which are formed integrally from a single piece of leather and the object of my improvement is to provide a shoe upper which will conform in shape to and nicely fit the ankle of the wearer without a heel seam and without removing any of the material in the rear of the upper to give the same the desired shape.

The construction of my shoe upper and the method of forming the same is explained by reference to the accompanying drawings in which,—

Figure 1 is a plan view of the upper as it is cut preparatory to being crimped and formed into a shoe. Fig. 2 is a shoe upper after it has been crimped and folded preparatory to attaching the same to the sole of the shoe, and Fig. 3 is a side view of a shoe as completed.

Like parts are identified by the same reference figures throughout the several views.

In forming a shoe a piece of leather is first cut in the shape shown in Fig. 1 from a single piece of leather, the outline of which comprises the horizontal cut from 1 to 2, the concave or curved cut from 2 to 3, the S-shaped curve from 3 to 4, the horizontal cut from 4 to 5, the semi-circular cut from 5 to 6, the S-shaped cut from 6 to 7 and the curved cut from 7 to 1. When the upper has been thus formed it is folded transversely on the dotted lines 8, 8, which forms the central vertical part of the heel portion. It will now be understood that when thus formed the heel portion from 8 to 8 will be straight and unsymmetrical substantially as shown in the Letters Patent to Skinner referred to and will not conform to or fit the ankle of the wearer. By my improved method the shoe upper when thus formed is placed in a crimp and the angular shaped portions of the upper included between the lines 10 and 11, 11 and

12, 12 and 10, and the upper side of the blank between the lines 13 and 14, 14 and 15, and 15 and 13 are stretched and expanded while the central portion of the shoe upper between the points 11 and 14 remain substantially in its normal condition. When the shoe upper has been thus stretched and expanded between the lines indicated the body portion of the upper will be proportionately extended upon the respective sides of the line 8, 8, as indicated by the dotted lines 16, 17, 18 and 19 when such extended portions are removed. This being done the blank is folded upon the line 8, 8 when the overlapping parts 19 and 20 are secured together by one or more stitches 21 when the same is ready to be attached to the sole of a shoe and the shoe will have a neat and symmetrical appearance as indicated in Fig. 3.

Having thus described my invention what I claim as new and desire to secure by Letters Patent is,—

The method herein described of forming a shoe upper from a single piece of leather having when made up a centrally inwardly curved rear portion without cutting or stitching such heel portion, consisting, first, in cutting the shoe upper comprising a toe portion, and a continuous heel, ankle, an instep portion formed integrally, one side of the front portion being provided with a slit extending forwardly toward the longitudinal center of the upper; second, crimping and expanding the upper and lower heel end portions of the upper thus formed, leaving the centrally inwardly curved portion of the upper in substantially its normal unexpanded condition; third, in removing the surplus end portions of the upper which is produced by the outward expansion of the upper and lower edges of the shoe upper, and fourth, in folding and stitching the overlapping side portions of the blank together, all substantially as and for the purpose specified.

In testimony whereof I affix my signature in the presence of two witnesses.

CHARLES R. SCHLEIFER.
